UNITED STATES PATENT OFFICE

FRANK BOWERS, OF DETROIT, MICHIGAN, ASSIGNOR TO DIAMOND POWER SPECIALTY CORPORATION, OF DETROIT, MICHIGAN, A CORPORATION OF MICHIGAN

LOCOMOTIVE SOOT BLOWER

Application filed October 30, 1922. Serial No. 597,991.

This invention relates to boiler cleaners and refers more particularly to boiler cleaners for blowing soot from the tube sheet and tubes of locomotive or similar boilers although the invention in its broader aspects is not limited to use with any particular type of boiler.

Among the objects of the invention are to provide a new and improved boiler cleaner which will effectively clean all the tubes of the boiler; to so construct and arrange the parts that a concentrated or solid jet of steam is directed against a relatively small area of the tube sheet, the jet successively covering all parts of the tube sheet.

Other objects of the invention are to provide a construction of soot blower in which the discharge can be made to trace a substantially rectilinear line and readily adjusted to cover each succeeding line of tubes; to provide a protection for the end of the blower; to provide improved means for projecting and retracting the blower nozzle; and the invention further resides in such other features of construction and arrangements and combinations of parts as will more fully hereinafter appear.

In the drawings:

Fig. 1 is a top plan view partly in section showing blowers embodying my invention applied to a locomotive boiler.

Figure 2 is a side elevation thereof.

Figure 3 is an end view of the boiler sheet.

Figure 4 is an enlarged horizontal section through one of the blower nozzles showing the parts in projected position;

Figure 5 is an end view of the blower shown in Figure 4;

Figure 6 is a view along the line 6—6 of Figure 4;

Figure 7 is a view along the line 7—7 of Figure 4;

Figure 8 is a view corresponding to Figure 4 showing the parts in withdrawn position;

Figure 9 is a detail elevation view of the segmental gear; and

Figure 10 is a side sectional elevation view of the segmental gear along 10—10 of Figure 9.

50 Describing first in detail the general ar-

angement of parts shown in Figure 1, A designates a locomotive boiler having the cab A', the fire-box B and the boiler tubes C which are mounted at one end in the tube sheet. For cleaning these tubes there are 55 located at the sides a pair of soot blowers D inserted through tubes D' extending through the water legs on each side of the boiler. These blowers are located a suitable distance back of the rear tube sheet B² with their nozzles K directed toward the tube sheet. To protect the nozzle from the heat of the fire box, the end of the blower may be formed with a relatively heavy portion P which, in the stored position of the nozzle (as shown 60 in Figure 8) entirely overlies the nozzle. Each of the blowers is connected up to a steam or other cleaning fluid supply by pipes F and controlled by valves F' conveniently located in the cab. F² denotes the body casting of the blowers, this casting being connected with the cleaning fluid supply pipes F as shown in Figures 4 and 8. For securing the body casting F² to the outer wall 65 of the fire box B, I may provide bolts F³ 70 extending at the opposite sides of the casting as shown in Figure 5. The operating rod G for turning the blowers terminates in a suitable hand wheel G' also located in the cab A' within convenient reach of the engineer 75 and fireman. When the steam is turned on it passes through the supply pipe F into the chamber H and here acting on the plunger H' forces the same forward carrying with it the plunger tube I and compressing the 80 spring I' until the thrust bearing I² is brought in contact with the spacer I³, the outer face of the thrust bearing bearing against the hub of the segmental gear J. The forward end of the spacer I³ bears 85 against the packing housing I⁴ which is rigidly secured to sleeve I⁵. The sleeve I⁵ is rigidly carried by the blower housing as at I⁶. As the plunger H' moves forward under the action of the steam the nozzle K 90 is forced inside of the inner wall of the water leg as shown in Figure 1 and the jet of steam from the nozzle K is directed against the tube sheet. It will be noticed that the entire stream is concentrated through a single 95 100

nozzle so that the steam is played with great force against a relatively small area of the tube sheet. Upon revolving the wheel G_2 within the limits allowed by the rod J^2 fixed to the housing and extending through the slot J^4 on the lower part of the segmental gear J , the plunger tube I will turn the plunger H' and the nozzle K through an arc of approximately 90 degrees, covering the boiler tubes in direct line with the nozzle either vertically the full height of the tube sheet or, if desired, the nozzle could be arranged to discharge along a horizontal line. The segmental gear J is fixed, as by a set screw J^6 , on the plunger tube I . Between plunger H' and plunger tube I is located a spider H^2 , secured to tube I by set screws H^3 which have inwardly extending fingers H^4 engageable in the circumferential groove H^5 of the rod J' so as to prevent relative longitudinal movement between rod J' and tube I , but to permit relative rotation of these parts. H^6 are other set screws for securing plunger H' with the spider H^2 , the set screws H^6 also serving to lock the set screws H^3 in place. As shown in Figure 7 the cleaning fluid is free to pass spider H^2 in travelling longitudinally in plunger H' .

In operation, before the steam is turned on the spring I' will hold the parts in the position shown in Figure 8, the nozzle being housed within the water leg of the boiler. When the steam is admitted to the blower through pipe F the nozzle K restricts the flow of steam sufficiently so that the plunger H' will be projected forwardly carrying with it plunger tube I and rod J' so that the segmental gear J will be carried forwardly on the plunger tube I to mesh with the bevel gear driven by the operating rod G . The spacer I^3 and thrust bearing I^2 will take up the thrust through the sleeve I^5 . The parts are now ready for operation by the rod G . The nozzle K is oscillated by movement of the rod G to describe substantially vertical lines up and down the flue sheet as hereinbefore described. The same operating means acting through a mechanism now to be described causes an angular movement of the nozzle K to cause this to advance in horizontal increments across the flue sheet, this advance taking place during the clockwise or right-hand movement of the segmental gear J .

The nozzle is provided with teeth L' cut to form a gear engaging the small gear L fixed to the end of shaft J' . During the counterclockwise or left-hand movement of segmental gear J the shaft J' rotates with the gear J as will be hereinafter described so that the nozzle K rotates with the plunger tube H' , there being no angular movement or change in direction of the nozzle K during this part of the cycle. When now, the segmental gear J is rotated in the clockwise, or righthand direction the shaft J' is held

against movement while the nozzle K is, of course, rotated. The gears L and L' thus act to move the nozzle in an angular direction, causing the steam jet to move in a horizontal increment across the flue sheet. This cycle is then repeated.

The segmental gear J is provided with an extension M^4 , on which extension is fixed the spring pawl M . This spring pawl is adapted to engage teeth in a ratchet wheel K^2 , which ratchet wheel is fixedly attached to shaft J' . Mounted loosely on the shaft J' is the housing M^2 , to which housing is fixedly attached a second spring pawl M' , also adapted to engage the teeth in ratchet wheel K^2 . This housing, M^2 is provided with a slot through which passes the rod J^2 . The set screw N is provided to regulate the amount of travel of the housing M^2 with reference to the rod J^2 , this amount of travel determining the horizontal advancing increment of the nozzle K .

Looking now at Figures 5 and 6, if the segmental gear J be rotating counter-clockwise, or to the left in these figures, the ratchet wheel K^2 will be also rotated by virtue of engagement therewith of the spring pawl M , mounted on projection M^4 of the gear J . At the same time, the spring pawl M' attached to housing M^2 exerts sufficient pressure against the teeth of the ratchet wheel K^2 to carry forward the housing M^2 until one end of the slot J^5 in said housing contacts with the rod J^2 . This movement is possible by virtue of the free movement of the housing M^2 on shaft J' and because of the spring pressure exerted by pawl M' in the teeth of the ratchet wheel.

After engagement of the rod J^2 with one end of the slot J^5 the travel of the housing ceases and the spring pawl M' simply clicks the teeth in ratchet wheel K^2 until the counter-clockwise movement of the parts has ceased. The limits of this movement, of course, are determined by engagement of the slot J^4 in gear J with the rod J^2 as hereinbefore described. It is obvious that shaft J' rotating with the ratchet wheel K^2 causes the nozzle K to act in unison with the movement of the other parts producing no change in the angular position of the nozzle.

When now, we reverse the direction of rotation of gear J , the spring pawl M will tend to move the ratchet wheel K^2 in the same direction by virtue of the pressure of the spring pawl M in the teeth of the ratchet.

Thus, the ratchet wheel K^2 moves in a clockwise direction, carrying with it the spring pawl M' and housing M^2 until the rod J^2 engages the set screw N . It should be pointed out that the housing M^2 is loosely mounted on shaft J' . When this point has been reached the pawl M' prevents further movement of the ratchet wheel K^2 , thus holding the shaft J stationary for the balance of the clockwise movement of the gear J . The

spring pawl M, carried by the gear, during this portion of the clockwise cycle, simply clicks over the teeth of the ratchet wheel K². It is obvious that if the ratchet K² and the shaft J' be held stationary while the nozzle K is being moved by virtue of its attachment to the plunger tube H' that the nozzle will be moved angularly by virtue of the engagement of the gears L and L', causing it to change its angle to the axis of the plunger tube.

What I claim as my invention is:

1. In a boiler cleaner, a fluid supply, a discharge nozzle for the fluid, a blower tube for the nozzle, means for normally holding the blower tube and nozzle in a retracted inoperative position, automatic means for advancing the blower tube and nozzle, means for rocking the blower tube and nozzle, and means for automatically periodically relatively moving the blower tube and nozzle.

2. The combination with a locomotive having a fire box, a water leg adjacent the fire box, and a cab, of a boiler cleaner having a discharge nozzle and mounted within the water leg of the boiler and projectable into the fire box, means for normally retaining the cleaner within the water leg, means for projecting the cleaner into the fire box, and common means operable from the cab of the locomotive for imparting movement in a plurality of directions to the nozzle, said common means automatically acting after movement of the boiler cleaner in one direction has been completed, to compel said nozzle to then move in another direction upon continued actuation of said common means.

3. The combination with a boiler flue sheet of a cleaning device therefor, said cleaning device being mounted to oscillate about an axis parallel to the plane of said sheet, said cleaning device being further provided with a nozzle for discharging a jet of cleaning fluid against the boiler flue sheet, means for rocking said nozzle, and nozzle adjusting means actuated by the means aforesaid to permit discharge of the cleaning fluid so as to trace on said flue sheet a series of lines spaced apart a predetermined amount, and means for varying the space between the said lines.

4. The combination with a boiler flue sheet, of a cleaning device therefor, said cleaning device being mounted to oscillate about an axis parallel to the plane of said flue sheet, said cleaning device being provided with a nozzle for discharging cleaning fluid, separate means for retracting and advancing the nozzle into inoperative and operative positions respectively, and means for imparting such movement to the nozzle as to cause the jet of cleaning fluid discharged thereby to trace a plurality of substantially straight spaced lines on the said flue sheet.

5. A boiler tube cleaner comprising a longitudinally extending tubular member closed

at one end and having an inlet opening adjacent to the other end, a nozzle rotatably mounted in a side of said member adjacent to said closed end and having its axis of discharge disposed at an angle to the axis of said nozzle, means for oscillating said member, and means actuated by the operation of said oscillating means for imparting a step by step rotary movement to the nozzle at corresponding points in the successive oscillations of the blower.

6. A boiler tube cleaner comprising a longitudinally extending tubular member closed at one end and having an inlet opening adjacent to the other end, a nozzle rotatably mounted in a side of said member adjacent to said closed end and having its axis of discharge disposed at an angle to the axis of said nozzle, means for oscillating said member, and means actuated by the operation of said oscillating means upon movement of the tubular member in one direction of its oscillatory movement to impart a step by step rotary movement to the nozzle.

7. A boiler tube cleaner comprising a longitudinally extending tubular member closed at one end and having an inlet opening adjacent to the other end, a nozzle rotatably mounted in a side of said member adjacent to said closed end and having its axis of discharge disposed at an angle to the axis of said nozzle, a shaft for rotating said nozzle, means for oscillating said member, and means operable to hold said shaft stationary during a predetermined portion of the oscillatory movement of said tubular member for imparting a rotary movement to the nozzle.

8. A boiler tube cleaner comprising a longitudinally extending tubular member closed at one end and having an inlet opening adjacent to the other end, a nozzle rotatably mounted in a side of said member adjacent to said closed end and having its axis of discharge disposed at an angle to the axis of said nozzle, a rotatable member for rotating said nozzle, means for oscillating said member, and means for preventing the rotation of said rotatable member during a predetermined portion of the oscillatory movement of said member to effect a rotation of the said nozzle.

In testimony whereof I affix my signature.
FRANK BOWERS.
